UNITED STATES PATENT OFFICE

2,458,884

EAR PROTECTOR VALVE

John Volkmann, Cambridge, Mass., assignor to the United States of America as represented by the Executive Secretary of the Office of Scientific Research and Development, and The President and Fellows of Harvard College

Application January 3, 1946, Serial No. 638,881

5 Claims. (Cl. 128—152)

1

This invention relates to acoustic devices and more particularly to an earplug member which includes valve means for opening and closing a communication channel through the earplug.

In connection with the use of acoustic devices of the character referred to, it may be desirable to hear a relatively weak acoustic signal and immediately thereafter to protect the ear against intermittent loud noises. An example is the situation of an infantryman firing a recoil-less weapon which is characterized by an exceedingly heavy discharge. The infantryman is required to hear a relatively low-voiced oral command and then to fire his weapon. Various other situations suggest themselves where the use of selectivity and flexibility in the operation of acoustic devices become highly important. The use of a telephone in noisy offices and factories may be greatly facilitated by some acoustic protection.

An object of the invention is to improve acoustic devices and to devise an earplug member which includes valve means for opening and closing a communication channel through the earplug member while the latter is inserted in an ear. Another object of the invention is to provide a simple, novel and efficient earplug member including valve means which may be operated either directly by hand or indirectly in connection with the use of other communication equipment. Other objects will appear from the following description.

In the accompanying drawings:

Figure 1 is a sectional view illustrating a preferred form of earplug member of the invention; and

Figure 2 is a cross section and partial elevation taken on the line 2—2 of Fig. 1.

The earplug of the invention in a preferred form is constructed from two separate units: an insert tip adapted to engage firmly within the auditory canal, and an external valve body secured to the insert tip. It is convenient to mould these two pieces separately since they are irregular in shape. The material used is highly elastic, manually deformable rubber or the like.

Referring more in detail to the drawings, 10 indicates the insert tip which is a generally L-shaped body of tubular construction, having a communication channel 12 extending all the way therethrough, as shown in Fig. 1. Its extremity is formed with a more yieldable sealing flange 14, hood-like and generally mushroom shaped, returning from the extremity of the tip, having thin edge portions so designed that a minimum of pressure is exerted on sensitive cartilage por-

tions of the ear passage in which the tip may be inserted. The tubular portion curves as shown in Fig. 1 to conform as nearly as possible to the contour of the average ear canal.

5 Secured to the tip 10 is the acoustic valve body 15 of the invention which may for example consist of an enlarged frusto-conical moulded rubber body formed at its smaller end with a coaxial tubular nipple 16 of a size to fit snugly within 10 the outer end of the tip 10. If desired, these two tubular members may be solidly secured together by cementing with a rubber cement or other adhesive. Preferably the valve body is formed with a shoulder at the base of the nipple 16 against which the tip abuts snugly, establishing a standard length for the tip 10.

The valve body is further formed with an axial communication channel 20 extending part way through as shown in Fig. 1, stopping in the larger 20 part of the body 15. At one side the valve body has been partly cut through along a plane normal to the body axis, the cut forming a closed slit which passes through roughly one-half of the body 15 in a plane normal to the axis of the 25 body and intersecting the communication channel 20 near its closed outer end. Adjacent to the outer side of the cut there is an integral thick diagonal arm 24 which extends longitudinally outward from the large end of, and divergent from 30 the axis of, the body 15. When the tab 24 is forced into a position such as the dotted line position indicated in Fig. 1, the opposed and normally closed portions of the valve body at the 35 sides of the cut are caused to move apart, thus forming an appreciable opening which communicates with the channel 20, as may be observed from the dotted line showing. Upon releasing the tab, the cut portions spring together in substantially sealed relation, thus closing the channel.

The arm 24 is preferably arranged on the valve body in a position such that it is adapted to extend out from the wearer's head in an offset manner and may be readily bent inwardly by pressing 45 with the finger. It may also be desired to operate the valve by pressing a telephone hand-set unit against the ear. This is entirely feasible with the arrangement described since the offset position of the tab lends itself very well to being pressed inwardly by the case of the telephone hand-set receiver.

The particular structure described may be varied in several respects. The entire plug member may be made up of a single piece of material 50 rather than being formed in two pieces and ce-

mented together. However, the two-piece type of construction has some advantages as the tip member has utility in various other connections. Similarly, the valve body may be provided with other means of opening and closing the passage through the earplug. For example, I may employ spring-operated valves of various types built into the valve body in some convenient manner. Various other types of earplug members, either with or without a sealing flange may also be combined with the valve means of the invention.

An insert tip of the character described, when closed, gives an average acoustic insulation of more than 20 decibels. The valve body in a sealed position provides a substantial closure and hence it also provides a similarly high degree of acoustic insulation. However, only a very slight opening of the valve permits passage of sound.

The device may be easily and cheaply manufactured and is simple to use and keep in working condition. It offers a quick and positive means of selectively insulating against noise while permitting speech communication when desired.

I claim:

1. An acoustic valve for an earplug comprising a slotted elastic manually deformable body portion connected to the plug, said body having a blind sound-communication passage therein intersecting the slit and open through one end of the body, and means for moving the portions beside the slit apart from one another.
2. An acoustic device comprising an insert tip for use in an ear canal, said tip having a communication channel therethrough, a valve body of elastic manually deformable material having a blind opening connecting with the communication channel, a slit being formed partly across the body and passage normally closed in the unstressed form of the device, and means for resiliently opening the slit at will.
3. An ear guard and valve comprising a frustoconical body of highly elastic manually deformable rubber-like material having a coaxial blind passage therein open on the smaller end and in-

cluding an ear-fitting tubular tip forming an open continuation of said passage, said body being slotted across the said passage, said slit being normally closed in the unstressed condition of the article, and a stiff arm united with the body at the outer side of the slit, manually operable to open the slit at will for admission of sound.

4. The structure of claim 3 wherein said arm is extended longitudinally outward and divergent from the axis of the device, whereby an object pressed toward the head over the ear will open the slit.

5. As an improved article of manufacture, an ear guard and valve comprising a body of elastic manually deformable rubber-like material including a tubular tip portion insertable in the auditory canal and an enlarged head portion at the outer end of the tip having a blind passage therein open to the extremity of the tip, said head forming a closed outer end for the tubular tip and constituting a stop to prevent insertion of the tip beyond a predetermined distance in the ear, said head being slit across from one side substantially normally to the axis of the body and so that the slit remains closed in the unstressed condition of the article, and an integral thickened valve-operating arm on the said enlarged body portion forming a continuation of the material beside and at the outer side of said slit.

Certificate of Correction

January 11, 1949.

Patent No. 2,458,884.

JOHN VOLKMANN

It is hereby certified that error appears in the above numbered patent requiring correction as follows:

The name of the assignee was erroneously described and specified as "United States of America as represented by the Executive Secretary of the Office of Scientific Research and Development, and The President and Fellows of Harvard College" whereas said name should have been described and specified as *United States of America as represented by the Executive Secretary of the Office of Scientific Research and Development*, as shown by the record of assignments in this office; and that the said Letters Patent should be read with this correction therein that the same may conform to the record of the case in the Patent Office.

Signed and sealed this 10th day of May, A. D. 1949.
